W. L. DRAKE.

Fire-Extinguishers for Railway-Cars.

No. 147,248.

Patented Feb. 10, 1874.

UNITED STATES PATENT OFFICE.

WEAR L. DRAKE, OF EVANSTON, ILLINOIS.

IMPROVEMENT IN FIRE-EXTINGUISHERS FOR RAILWAY-CARS.

Specification forming part of Letters Patent No. 147,248, dated February 10, 1874; application filed February 27, 1873.

CASE D.

To all whom it may concern:

Be it known that I, WEAR L. DRAKE, of Evanston, in the county of Cook and State of Illinois, have invented certain new and useful Improvements relating to Fire-Extinguishers, of which improvements the following is a full, clear, and exact description, which will enable others skilled in the art to which my invention appertains to make and use the same, reference being had to the accompanying drawing forming a part hereof, and in which—

Figure 1 represents a vertical section of a railway-car provided with my improved extinguisher in combination with the stove, and Fig. 2 an end view of the extinguisher.

Like letters of reference indicate like parts.

My invention consists in combining a self-rotary fire-extinguisher with the stove of a railway-car in such a manner that the contents of the extinguisher may be discharged into the stove through a fixed or non-rotating discharge-pipe, by means of a manual operation, at any time, and automatically by reason of an accident which otherwise might result in setting the car on fire. It also consists in certain novel features relating to the means employed for the purpose of rendering the extinguisher self-rotary, and for the purpose of connecting a rotary extinguisher to a discharge-pipe, so that the latter will not be affected by the rotary movement of the extinguisher.

In the drawing, A represents an extinguisher. B is the stove. C is the discharge-pipe. D is the reservoir of the extinguisher. The discharge-pipe communicates with the stove and with the reservoir, so that the contents of the latter may be discharged into the stove for the purpose of extinguishing the fire, as will be hereinafter more fully explained. E is the supporting-frame of the extinguisher. E' E' E' are friction-rollers pivoted to each end of the frame E at about equal distances apart, and in the line of a full circle. F is an annular rib or flange projecting laterally from each end of the reservoir, and resting on the rollers E'. The reservoir is thus rendered capable of a rotary movement. G is a coiled spring, one end of which is attached to the frame and the other end to the reservoir. When the reservoir is

turned in a direction opposite to the direction of the force of the spring and released, the action of the spring rotates the reservoir until the force of the spring is expended. The reservoir is thus rendered self-rotary. H is a stop-pin on the reservoir, and I is a lever pivoted to the frame and engaging with the pin H, thereby retaining the reservoir in position while the force of the spring G is being exerted upon it. The lever I may be drawn from its engagement with the pin H at any time by a manual operation. H' is also a stop-pin on the frame. The pins H and H' are arranged to engage each other, and thereby limit the rotary movement of the reservoir when it is operated upon by the spring G. J is the car-truck. The lever I extends to the truck, and is arranged between the truck-frame and a pin j. The distance between the frame and the pin j is such that neither the truck nor the pin j will be brought into contact with the lever I under ordinary circumstances; but an unusual movement of the truck, such as would be liable to occur in case of a serious accident, will throw the lever from its engagement with the pin H, and thereby set the extinguisher in operation.

The extinguisher herein represented belongs to that class from which the contents are discharged by means of gas generated in the extinguisher, and which is set in operation by being tilted or inverted, and that part of my invention which relates to the extinguisher alone has reference to an extinguisher of the class above set forth; but any extinguisher under the control of an operator, or which may be set in operation automatically, may be combined with the stove, so that the contents of the extinguisher will be discharged into the stove through a discharge-pipe communicating with both. I deem it preferable, however, to employ, for the purposes set forth, an extinguisher of the class herein shown and particularly described; and when an extinguisher of this class is provided with a discharge-pipe, C, and employed for this and for other purposes, it is essential that the said pipe should not be affected by the movement of the reservoir.

I therefore attach the pipe C to the reservoir in the following manner: C' is the head of the

pipe C, and is matched to the tubular projection C'', extending a short way horizontally from one end of the reservoir, as shown in Fig. 3. K is an annular packing interposed between the end of the head C' and the end of the tube C''. L is a clamp or clevis engaging the head C' and set loosely on the tube C'', and behind the shoulder c. L' is a wedge-shaped key passing through slots or perforations in the clamp L, so as to hold the head L firmly against its packing. I deem it preferable to bevel the head C' and the end of the tube C'', as shown, so as to make a firm joint. In other words, the pipe C is loose-jointed to the reservoir, but rendered water-tight, and it is unaffected by the movement of the reservoir.

Having thus described my invention, what I claim as new, and desire to secure by Letters Patent, is—

1. A self-rotary fire-extinguisher provided with a fixed or non-rotating discharge-pipe, arranged to conduct the contents of the extin-

guisher into the stove of a railway-car during the operation of the extinguisher, substantially as and for the purposes specified.

2. A rotary fire-extinguisher, in combination with friction-rollers constituting the bearing of the reservoir, substantially as specified.

3. The spring G, or its equivalent, in combination with a rotary fire-extinguisher, and constituting the means by which the reservoir is rotated, substantially as specified.

4. The pivoted lever I, in combination with the pin H of a self-rotary fire-extinguisher, substantially as and for the purposes specified.

5. The discharge-pipe C, in combination with a rotary fire-extinguisher, and rendered unaffected during the rotary movement of the reservoir by means of a loose-jointed attachment to the latter.

WEAR L. DRAKE.
